UNITED STATES PATENT OFFICE.

JOSEPH DAUBER, OF LAFAYETTE, INDIANA, ASSIGNOR TO THE INDIANA WAGON COMPANY, OF LAFAYETTE, INDIANA, A CORPORATION OF INDIANA.

TOP-BOX FASTENER FOR WAGONS.

SPECIFICATION forming part of Letters Patent No. 783,623, dated February 28, 1905.

Application filed November 5, 1904. Serial No. 231,487.

To all whom it may concern:

Be it known that I, JOSEPH DAUBER, a citizen of the United States, residing at Lafayette, in the county of Tippecanoe and State of Indiana, have invented certain new and useful Improvements in Top-Box Fasteners for Wagons, of which the following is a specification.

The object of my invention is to produce a neat and effective device by means of which an extension-box may be easily and quickly adjusted to the lower or main box-body of a wagon.

The accompanying drawings illustrate my invention.

Figure 1 is a side elevation of a wagon-body provided with my improved attachment. Fig. 2 is a side elevation of the attachment full size, and Fig. 3 is a vertical section of the parts shown in Fig. 1.

In the drawings, 10 indicates the lower and usual box-body, and 11 the usual extension-box. Secured to box 11 at convenient points is a plate or bar 12, to the lower end of which is pivoted a lever 13. Lever 13 is provided with a finger 14, which lies parallel with the main body of the lever and extends to one side of the pivot thereof, thus providing the lever with a bifurcated end. The pivot 13' is preferably formed integral with the body of the lever and secured to the plate 12 by riveting, as shown in Fig. 3. Lever 13, to one side of the pivot 13', is perforated at 15, and the finger 14 is correspondingly perforated at 16, the two perforations being in alignment and adapted to receive the trunnions 17 of a bar 18, provided through its main body with a tapered perforation 19, the axis of which is substantially at right angles to the axis of the trunnions 17. Passing loosely through perforation 19 is a fastening-rod 20, which is threaded at its upper end and provided with a nut 21, adapted to engage the upper side of bar 18. By this means the effective length of rod 20 may be quickly adjusted so that the parts may be brought together with sufficient tightness. Rod 20 is provided at its lower end with an inturned finger 21', adapted to enter an opening 22, formed in a

plate 23, secured to the wagon-body 10 in alignment with the plate 12.

The free end of lever 13 is provided at its outer end with a finger-piece 24, by means of which it may be easily swung, and at an intermediate point is provided with a finger 25, which when the parts are in the position shown in full lines in Fig. 2 overlies the rod 20 and prevents any possibility of displacement of the finger 21' thereof from the slot 22 of plate 23. The lever 13 is preferably a casting of malleable metal, and in its initial condition the finger 14 diverges from the main body of the lever a distance equal to or slightly greater than the combined length of the two trunnions 17. The holes 15 and 16 are formed initially in the casting, and the perforation 19 is also formed in the casting 18, so that the parts may be assembled without machine-work of any kind, the cross-bars being introduced between the main body of the lever 13 and the finger 14 with the trunnions 17 in alignment with the perforations 15 and 16, and the finger 14 then bent into parallelism with the main body of the lever.

In operation the extension-box 11 is placed in position upon the lower or main box 10 and the finger 21 of rod 20 introduced into the perforation 22 of plate 23, the parts being in the position shown in dotted lines in Fig. 2. Thereupon the operator swings lever 13 into the position shown in full lines in Fig. 2, thus drawing the plate 12 toward the plate 23 and bringing the body 11 down tightly upon the body 10. When in this position, the axis of rod 20 passes through the plane of the axis of 13' or slightly between said axis and the arm 13, so that there is no danger of displacement of the parts by an accidental swinging of lever 13. The finger 25 prevents any possibility of a rod 20 being jolted transversely so as to withdraw finger 21' from plate 23.

I claim as my invention—

1. A fastening device consisting of a pivoted lever, having a bifurcated end, a cross-bar pivotally supported between the arms of said bifurcated end and having a transverse per-

foration, a fastening-rod passing freely through said perforation and provided with a retaining-head at one end and a fastening device at the other, and a finger carried by the lever and adapted to overhang the fastening-rod in one position of the lever.

2. The combination, with the main box-body of a wagon, of an extension-box therefor, a fastening-lever pivoted to one of said body parts to swing in the plane substantially paralleled therewith, and a fastening-rod swiveled to one end of said lever and provided at its free end with an engaging device adapted to engage a portion carried by the other of said body parts.

3. The combination, with the main box-body of a wagon, of an extension-box therefor, a fastening-lever pivoted to one of said parts, a fastening-rod swiveled to one end thereof and provided at its free end with an engaging device adapted to engage a portion carried by the other of said body parts, and a finger carried by the lever and adapted to overhang the fastening-rod when in one position to prevent lateral displacement thereof.

4. The combination, with a main box-body of a wagon, and an extension-box therefor, of a plate secured to one of said body parts, a lever pivoted to said plate and provided with a bifurcated end, a cross-bar pivotally mounted between the arms of said bifurcated ends and provided with a transverse perforation, a fastening-rod passing freely through said transverse perforation and provided at one end with a retaining-head and at the other end with an engaging device, and a coöperating engaging device carried by the other body part.

5. The combination, with a main box-body of a wagon, and an extension-box therefor, of

a plate secured to one of said body parts, a lever pivoted to said plate and provided with a bifurcated end, a cross-bar pivotally mounted between the arms of said bifurcated end and provided with a transverse perforation, a fastening-rod passing freely through said transverse perforation and provided at one end with a retaining-head and at the other end with an engaging device, a coöperating engaging device carried by the other body part, and a finger carried by the lever and arranged to overhang said fastening-rod in one position to prevent lateral displacement thereof.

6. A fastening device consisting of a pivoted lever, having a bifurcated end, a cross-bar pivotally supported between the arms of said bifurcated end and having a transverse perforation, a fastening-rod passing freely through said perforation and provided with a retaining-head at one end and an engaging device at the other end, and means for adjusting the effective length of said fastening-rod.

7. A fastening device consisting of a pivoted lever, having a bifurcated end, a cross-bar pivotally supported between the arms of said bifurcated end and having a transverse perforation, a fastening-rod passing freely through said perforation and provided at one end with a longitudinally-adjustable retaining-head adapted to engage the cross-bar and at the other end provided with an engaging device.

In witness whereof I have hereunto set my hand and seal, at Lafayette, Indiana, this 12th day of October, A. D. 1904.

JOSEPH DAUBER. [L. S.]
